UNITED STATES PATENT OFFICE.

JOHN M. BLONDELL, OF BALTIMORE, MARYLAND, ASSIGNOR TO FREDERICK E. TOBE, OF SAME PLACE.

RAILWAY-CAR BRAKE.

SPECIFICATION forming part of Letters Patent No. 449,645, dated March 31, 1891.

Application filed August 7, 1890. Serial No. 361,379. (No model.)

To all whom it may concern:

Be it known that I, JOHN M. BLONDELL, a citizen of the United States, residing at Baltimore, in the State of Maryland, have invented 5 certain new and useful Improvements in Railway-Car Brakes; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

My invention relates to brakes for railway-cars; and it consists of certain novel parts and combinations of parts, the separate features of which will be separately and specifically pointed out in the claims concluding this specification.

20 My improvement is particularly directed to a device for coupling the brake-bar to its operating-rod, whereby to obtain a more accurate adjustability of the brake-shoes to the face of the wheel under varying conditions 25 due to the rising and falling of the body of the car and by the settling of the springs or overloading of the cars, to relieve the wear upon the brake-rod, and to prevent the splitting of the brake-bar, which is liable to occur 30 from the twisting and tortuous action of both bar and rod.

Referring to the accompanying drawings, Figure 1 represents in top view a portion of the brake-bar, which carries the brake-shoes and my improved self-adjusting coupling device connected to a portion of the brake-operating rod. Fig. 2 is a vertical section of the same, showing the adjustable coupling device in position when the brakes are applied. 40 Fig. 3 shows a similar view when the brakes are released, and Fig. 4 shows the flanged plate for connecting the coupling device to the brake-bar.

In the drawings I have only shown that portion of the brake-bar *a* to which the operating coupling device is secured; but it will be understood that the bar has the usual brake-shoe at each end thereof, and that the brake-operating coupling device is secured to the 45 middle of the length of said bar, and that the

latter is suspended in the usual way from a truck or body of the car.

The device which couples the brake-bar *a* to the operating-rod *b*, and which constitutes my improvement, consists of two short rods *c*, 55 one placed on the top and the other on the bottom of said bar, a link *d* for connecting them together and to the end of the operating-rod *b*, and a flanged plate *e* for connecting said rods to the outer side of the brake-bar to form 60 a coupling device in which the link-jointed rods are free to have a reciprocating movement through the flanged plate. This plate has two flanges or sides *f*, which fit upon the upper and upon the under sides of the brake-bar, and 65 the plate is secured upon the outer side of said bar by screw-bolts *g*, which pass through the bar and are provided with fastening-nuts. The plate is long enough to form a good bearing on the bar and to strengthen it at the 70 point where the power of the operating-rod is exerted in applying the brakes. At the top and at the bottom the side plates are formed with strong bosses *h*, through openings in which the coupling-rods are passed, and are 75 screw-threaded at their non-connected ends to receive sleeved nuts *i*, which secure the rods to the said plate and serve to inclose the screw-threaded portions of said bolts to protect them against dust and rust. 80

The brake-operating rod is connected to the link centrally between the coupling-rods, so that in pulling the operating-rod the coupling-rods are drawn in with their sleeved nuts against the flanged plate to apply the brake-shoes, and in releasing the brakes both or either of the rods are free to slide back through the flanged plate to allow the brakes to fall away from the wheels. This freedom of the coupling-rods for independent movement results from their link-connection and the manner of connecting the operating-rod to the link, so that the latter is free to have a rocking movement upon its central pivot-connection. The advantages of this brake-bar-coupling device are that it causes the brake-shoes to be presented fairly to the faces of the wheels more in a line with the axle without tendency to fall below their proper 95 relation to the wheels, relieves the brake-bar 100

from all splitting strain from the action of the operating-rod, and saves the rod itself from being twisted and distorted and broken by the strain. It adjusts itself to the movement of 5 the brake-bar in such a manner as to cause the brake-bar with its shoes to be brought up to their work with greater directness and effect, and insuring thereby prompt control of the car and safety to the brake and to the car 10 and to the passengers.

A matter of special importance is that the rocking link-motion and its two coupling-rods by their action remove all liability to undue straining, twisting, and breaking of the 15 brake-operating rod or coupling device.

Referring to the action of the device which connects the middle of the suspended brake-bar *a* with the brake-operating rod, it will be understood that if the brake-operating rod 20 were rigidly connected to the brake-bar such rigid connection would be liable to split the bar or to twist the rod by the strain and force applied to the brake-bar in bringing the 25 brakes into action. The self-adjusting pivotal and sliding connection of the bar with the rod prevents this injury to bar or rod by allowing the bar and its attached shoes to be brought equally against the wheels, so that there can be no splitting strain upon either 30 end of the bar. The pivotal sliding connection for the brake-bar and the brake-rod allows the connection of the latter with the car-body to rise and fall with the latter without affecting the relation of the brake-bar and its 35 shoes with the wheels, because the rod, being pivoted at its brake-bar sliding connection, gives freedom for the rod to turn upon such pivot connection under the rising and falling of the car upon its springs without disturbing 40 the brake-bar, as it would do if the rod were rigidly connected to said bar.

I claim as my improvement—

1. In a railway-car brake, the combination, with the brake-bar and the brake-operating rod, of a device connecting these parts pivotally connected to the brake-operating rod and secured to the brake-bar by a connection freely sliding thereon longitudinally within certain limits, substantially as described, for the purpose specified. 45

2. In a railway-car brake, the combination of the brake-bar and the brake-operating rod with a device for coupling these two parts, consisting of rods above and below the bar, a link connecting their inner ends and the said 55 brake-operating rod, a plate secured to said car having openings through which said coupling-rods pass, and nuts upon the non-connected ends of the said rods.

3. In a railway-car brake, the brake-bar having a flanged plate secured on its outer side and having openings at each flanged side, in combination with rods passing through said openings, having screw-sleeves on their outer ends, a link connecting their inner ends, and the 65 brake-operating rod connected to said link between its end connections, for the purpose stated.

4. The combination, in a railway-car brake, the brake-bar having a flanged strengthening- 70 plate secured to its outer side, the brake-operating rod, and independent coupling-rods above and below said bar suitably jointed to said brake-operating rod, having a free sliding connection within said bar-plate, and provided with nuts. 75

In testimony whereof I affix my signature in presence of two witnesses.

JOHN M. BLONDELL.
